US00D962182S

(12) **United States Design Patent** (10) Patent No.: **US D962,182 S**
Chiu et al. (45) Date of Patent: **** Aug. 30, 2022**

(54) **RETICLE POD CONNECTING FRAME**

(71) Applicant: **Gudeng Precision Industrial CO., LTD.**, New Taipei (TW)

(72) Inventors: **Ming-Chien Chiu**, New Taipei (TW); **Yung-Chin Pan**, New Taipei (TW); **Hsiao-Chia Lo**, New Taipei (TW)

(73) Assignee: **GUDENG PRECISION INDUSTRIAL CO., LTD.**, New Taipei (TW)

(**) Term: **15 Years**

(21) Appl. No.: **29/696,000**

(22) Filed: **Jun. 24, 2019**

(30) **Foreign Application Priority Data**

Mar. 27, 2019 (TW) 108301726

(57) **CLAIM**

The ornamental design for a reticle pod connecting frame, as shown and described.

DESCRIPTION

FIG. 1 is a front, bottom and right perspective view of a reticle pod connecting frame showing the claimed design; FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The dashed broken lines in the figures show portions of the reticle pod connecting frame that form no part of the claimed design.

1 Claim, 7 Drawing Sheets
